CONCRETE CUTTING DEVICE

George W. Hirth, Milwaukee, Wis.

Application March 18, 1939, Serial No. 262,794

8 Claims. (Cl. 262—20)

My invention relates to concrete cutting machines and more particularly to a type of machine that may be employed to cutting pre-determined radius and constructed in a manner to make it portable so that it can be conveyed from one job to another.

Another object of my invention is to produce a device of the character described that may be mounted on rails or on rubber tires or a combination of both, in which event the rail is the guiding factor in determining the path of the device.

Still another object of my invention is to provide such a device that is adaptable to be driven by either an electric motor or an internal combustion engine depending on the location and the facilities available.

A still further object of my invention is to incorporate in the cutting device a surfacing device which may be considered an auxiliary accessory making the device adaptable for both cutting and surfacing without necessitating complicated mechanical changes.

It is manifest to anyone familiar with the art that a device as specified and illustrated provided a very practical means of accomplishing the purpose for which it is intended and the method employed for mounting the device affords a very practical means of lowering and raising the contact wheels from the surface of the concrete without any great amount of effort on the part of the operator.

Other and further objects of my invention will become more apparent as the description proceeds when taken in conjunction with the drawings which form a part of the specification and in which

Figure 1 shows a plan view of the device mounted on one track and on rubber tire wheels. This plan view also shows both the cutting and surfacing devices in position.

Figure 2 is a cross-sectional view of the device taken at the line 2—2 in Figure 1 illustrating the manner in which the resilient members support the device.

Figure 3 is a fragmentary perspective view of the surfacing device.

Figure 4 is an end view of Figure 3.

Figure 5 is a cross-sectional view of the resilient support members taken at line 5—5 in Figure 1, and

Figure 6 is a cross-sectional view of the resilient support members taken at line 6—6 of Figure 1.

55 Similar characters of reference indicate corre-

sponding parts throughout the several views and referring now to the same Figure 10 is a plate constituting the body of the device. This plate 10 is mounted on a rear axle 11 supported on wheels 12 and fastened to the plate 10 by means of the bearings 13. The forward end of the plate 10 has a recess 14 in which is positioned a plate 15 pivotally mounted to the plate 10 on an axle 16 journaled in bearings 17 as shown.

A handle 18 fastened to the plate 10 at 19 is employed by the operator to manipulate the device forward and backward and also by exerting downward pressure to the handle 18 the device may be lowered and raised against the spring pressure of the resilient members 20 which are pivotally supported by bearings 21 on the plate 15 and a cross member 22 supported by end plates 23 and 23' and journaled therein. In Figure 1, I show a rail 24 having flat members 25 and 25' supporting the rail 24 and flanged wheels 26 and 26' supported by the rear axle 27 and the front axle 11. The rear axle 27 is mounted to the plate 15 by means of bearings 28. There is a driven shaft 29 mounted to the plate 10 by means of bearings 30 and 30'. This driven shaft 29 is actuated and revolved by means of a belt 31 engaging a pulley 32 on the shaft 29 being driven from a pulley 33 mounted onto the power medium 34 which is shown as an internal combustion engine in Figures 1 and 2. This however may be an electric motor or any other means for furnishing the motive power. The shaft 29 is shown supporting an abrasive disc 35, held securely by the flanges 36 and 36'. This abrasive disc 35 is used as a cutting means for concrete when pressure is applied to the handle 18 forcing the entire device downward and causing the disc 35 to contact the concrete surface at the point 37. On the other end of the shaft 29 is shown an angular bearing 38, the shaft 29 having a bevelled gear 39 keyed to its end extends through the angular bearing 38 permitting the gear 39 to contact another bevelled gear 40 which is mounted to a vertical shaft 41 supported by the depending end of the angular bearing 38 at 42. This arrangement permits the attachment of a surfacing disc 43 to the end of the vertical shaft 41 and when the surfacing disc 43 is not to be used it may be removed from the driven shaft 29 and only the cutting disc 35 employed.

In the chosen embodiment of my invention exemplified by the accompanying drawings there are present certain novel refinements and improvements not heretofore disclosed in the prior art, however, it will be manifest to persons skilled

in the art that many changes in the general arrangement form and configuration of the structure may be made and parts thereof may be varied without departing from the spirit of my invention as set forth in the appended claims, what I claim and desire to secure by Letters Patent in the United States, is:

1. A device of the character described comprising in combination a body, an auxiliary plate hingedly supported to said body, a pair of wheels rotatably mounted to said body, a pair of wheels rotatably mounted to said auxiliary plate, a handle attached to said body to permit movement of the device on said wheels, resilient members on said body to pivotally support said auxiliary plate, an actuating means mounted onto said body, a drive shaft, said drive shaft journaled in bearings mounted to said body in a position between the wheels on said body and the hinged support of said auxiliary plate, means for rotating said driven shaft from said actuating means when said actuating means is in operation and a cutting disc mounted to the one end of said driven shaft, said disc employed for cutting concrete or the like when it is brought in contact with said concrete by pressure applied against the resilient members.

2. A device as described in claim 1 in combination with a horizontal track wherein one of each pair of wheels is flanged so as to permit engagement of said track thereby guiding the device in its forward and backward path during the cutting operation.

3. A device of the character described comprising in combination a body, an auxiliary plate hingedly supported at one end to said body, a pair of wheels rotatably mounted to the depending end of said body and said auxiliary plate, a handle attached to said body to permit the operator to move the device forward and backward, resilient members mounted between said auxiliary plate and said body to pivotally support said auxiliary plate, power actuated means mounted to said body, a driven shaft journaled in bearings supported on said body between the wheels on the depending end of said body and the hinged support of said auxiliary plate, said driven shaft provided with a pulley, means for connecting said pulley to said actuating means, one end of said driven shaft provided with a bevelled gear, a vertical shaft, said vertical shaft provided with a bevelled gear engaging the gear on said driven shaft and a surfacing disc mounted on the depending end of said vertical shaft for contact with concrete or the like when said disc is brought down into engagement by pressure applied against the resilient means on said auxiliary plate.

4. A device as described in claim 3 in combination with a horizontal rail, one of each of said pair of wheels flanged to accommodate said rail there-

by guiding the device in its forward and backward path.

5. A device of the character described comprising a horizontal body, an auxiliary plate hingedly supported to said body, wheels rotatably mounted to the depending end of said body and said auxiliary plate, resilient means pivotally supporting said auxiliary plate to said body, a handle attached to said body for use by the operator when conveying the device on said wheels, a power operated actuating means mounted on said body, a driven shaft journaled in bearings mounted onto said body plate at a point between the depending end of said body and said auxiliary plate mounting, support means for rotating said driven shaft when said actuating means is in operation, an abrasive disc, said disc mounted to one end of said driven shaft, an angular bearing mounted to the other end of said driven shaft, a vertical shaft, said angular bearing supporting a pair of bevelled gears operating said vertical shaft, and a surfacing disc, said surfacing disc attached to the depending lower end of said vertical shaft, both said abrasive disc and surfacing disc to be slidably mounted so that either one or the other may be removed at will.

6. A device as described in claim 5 in combination with a pair of rails, said wheels adapted for engagement with said rails to guide the device in its forward and backward path when moved by the operator.

7. A device of the character described, comprising a horizontal body, an auxiliary plate hinged to said body, wheels rotatably mounted to the depending ends of said body and auxiliary plate, resilient means pivotally supporting said auxiliary plate to said body, a handle attached to said body for conveying the device on said wheels, a power operated actuating means mounted on said body, a driven shaft, bearings mounted on said body at a point between the depending end of said body and the auxiliary plate mounting, said driven shaft journaled in said bearings, means for rotating said driven shaft when said operating means is in action, a cutting saw, said saw slidably mounted onto one end of said driven shaft, an angular bearing pendulously mounted to the other end of said driven shaft, a vertical shaft journaled in said angular bearing, a pair of bevelled gears on said driven shaft and vertical shaft, said gears engaging one another, and a surfacing disc slidably attached to the lower end of said vertical shaft for contact with the floor surface when pressure is applied to said handle.

8. A device as described in claim 7 in combination with one or more rails for guiding the device in its forward and backward path when moved by the operator.
